DES. 1984

Letters Pat. No. 145,734 Dated Aug. 10, 1884.

Design for the Plate of a Stove.

The schedule referred to in these letters Patents not making, part of the same.

To all whom it may concern:

Be it known that Daniel E. Paris of the City of Troy, in the County of Rensselaer, and State of New York, have invented, or produced a new and original ornamental design for Stove Plates and I do hereby declare that the following is a full and exact description of the same, reference being had to the annexed photographic drawing of a stove plate having my said ornamental design.

This ornamental design consists of a border or panel moulding A, two hinge straps B. C. and a compound central ornament C. shaped and arranged together as a stove door or plate seal to present the appearance shown by the photograph hereto annexed.

What I claim as new and of my invention or production and desire to secure by Letters Patent is - The herein above described ornamental design for a stove plate.

In testimony whereof, I hereunto set my hand this sixteenth day of July eighteen hundred and sixty-four.
